A. F. SCHROEDER.
REINFORCING DEVICE.
APPLICATION FILED FEB. 3, 1917.

1,268,887.

Patented June 11, 1918.

Inventor:
Albert F. Schroeder

by his atty

Carl B. Mueller

UNITED STATES PATENT OFFICE.

ALBERT F. SCHROEDER, OF CLEVELAND, OHIO.

REINFORCING DEVICE.

1,268,887.

Specification of Letters Patent. Patented June 11, 1918.

Application filed February 3, 1917. Serial No. 146,326.

To all whom it may concern:

Be it known that I, ALBERT F. SCHROEDER, a citizen of the United States, residing at city of Cleveland, in the county of Cuyahoga and State of Ohio, have invented a new and useful Improvement in Reinforcing Devices, of which the following is a specification, the principle of the invention being herein explained and the best mode in which 5 I have contemplated applying that principle, so as to distinguish it from other inventions.

My invention is associated with a reinforcing device or a metallic tie brace adapted to be embedded in concrete construction. 15 More particularly, the invention relates to a member adapted to connect and hold a series of primary reinforcing rods in proper spaced relation, during the pouring of 20 durating material thereabout.

The object of my invention besides contriving a structural design, which will be economical of manufacture and light in weight yet strong, is to supply the same with 25 certain features which facilitate its intended use in practice.

With the foregoing and other objects in view the invention consists of the novel construction, combination and arrangement of 30 parts as hereinafter more specifically described and illustrated in the accompanying drawings, wherein is shown an embodiment of the invention, but it is to be understood that changes, variations and modifications 35 can be resorted to which come within the scope of the claim hereunto appended.

Adverting to the drawing:

Figure I illustrates an elevation of a reinforcing device embodying my invention. 40 Fig. II is a bottom plan of Fig. I. Fig. III is a top plan of Fig. I. Fig. IV is a section on line IV—IV of Fig. I.

Fig. V illustrates a series of members embodying my invention as used preparatory to being embedded in a reinforced concrete beam.

The form which the drawing illustrates for my invention is I-shaped and as such is 50 adapted for use in the manufacture of concrete I-beams or trussed flooring, in which a plurality of parallelly extending rods are to be embedded.

The structure exemplified is a sheet metal 55 stamping which commends itself to commercial use because it may be made from

scrap material. In shape it comprises two substantially parallel end members 1 and 2, connected midway by a member, 3. The member 1, should be considered as that portion of the whole which will rest nearest the bottom of the beam and it will be seen to have intermediate strengthening ribs 4, and comparatively thin flat ends 5, each of which is fashioned with a cut-out portion having 60 a mainly circular part 6, and a constricted part 7, opening through the upper edge. The inherent flexibility of the metal will permit of bending the hooked extremities 8, so as to allow the insertion of the primary 70 reinforcing rods 9, after which the hook portions 8, may be returned to a position substantially within the plane of the ends 5, to thereby prevent the dislodgment of the rods. 75

The connecting web member 3, divaricates and connects with the member 1 in such a way as to inclose a large circular opening 10, through which the larger primary reinforcing rod 11, is to extend. The member 3, 80 is stiffened by a ribbed formation throughout its extent.

The upper member 2, is similarly provided intermediately of its ends with ribbed portions 12, and with flat end portions 13 85 and likewise with cut-out portions 14, all of such a shape as to provide hooks 15, capable of being bent laterally. In addition, the upper member 2, is provided at its middle with an upwardly, directed flat extension 16, 90 and this latter is similarly provided with the same type of cut-out 17, to form a hook 18. Other rods 9 appear occupying the cut-out portions 14.

The special advantage which my invention has over devices heretofore used is due to the idea of slotting through the openings which are to accommodate the majority of the reinforcing rods, so that the entire rod may be simultaneously inserted in a row of 95 openings instead of being separately inserted through each opening. In operation after the requisite number of devices like that which constitutes the subject matter of this application have been collected upon the rod 100 11, the other five smaller rods may be very quickly inserted into the alined openings 6, 14 and 17 respectively, and thereafter locked therein by bending the hooks 8, 15 and 18 back to the near closing position seen in 110 Figs. I and V. It is to be understood that devices of this character may be supplied to

the trade with the hooks 8, 15 and 18 already bent out of the plane of the opening as shown in Figs. II and III so that the assembly of the reinforcing structure in its entirety may be the more speedily effected.

During the manufacture of I beams the stamping is suspended in the mold against the lower sides of the upper member 2, otherwise the weight of the rods would depress it below its proper position. In order to minimize the portion of the stamping which will thus become flush with the under surface of the indurated material there, I bring such two lower sides to a point at 19, thereby concealing all of the stamping with the exception of such points as will be readily understood by those skilled in the art.

I claim:

A reinforcing device of the character described comprising a skeleton member having a plurality of ends thin, substantially flat and somewhat flexible, such ends being furthermore fashioned with cut-off portions, having constricted communication through an edge of the member respectively, whereby the flexing of the material bordering said constricted cut-out area enables the insertion of an object fitted to the remainder of the cut-out area, some of said ends being fashioned with points for the purpose specified.

Signed by me, this 25th day of January, 1917.

ALBERT F. SCHROEDER.
